UNITED STATES PATENT OFFICE.

JOSHUA B. BARNES, OF SPRINGFIELD, ILLINOIS.

BRAKE-BEAM.

No. 846,819.

Specification of Letters Patent.

Patented March 12, 1907.

Application filed October 18, 1906. Serial No. 339,528.

To all whom it may concern:

Be it known that I, JOSHUA B. BARNES, a citizen of the United States, residing at Springfield, in the county of Sangamon and State of Illinois, have invented a new and useful Improvement in Brake-Beams for Railroad-Cars, of which the following is a specification.

My invention relates to an improvement in that part of the air-brake gear of a railroad-car known as the "brake-beam" or "bar," in connection with the brake-lever, and having the brake-heads attached thereto, and has for its object to provide a light and strong brake-beam of simple inexpensive construction and particularly adapted for resisting strain in emergency cases.

The invention consists in features of novelty, as hereinafter described and claimed, reference being had to the accompanying drawing, forming part of this specification, whereon—

Figure 1 is a top plan view of my improved brake-beam, showing the brake-heads attached thereto; Fig. 2, a cross-section, to enlarged scale, through the compression and tension members of the brake-beam on line 2 in Fig. 1, showing the combined king-post and brake-lever fulcrum (hereinafter termed "brake-lever fulcrum") in corresponding elevation; Figs. 3 and 4, vertical cross-sections thereof on lines 3 3 and 4 4, respectively, in Fig. 2; Fig. 5, an end view, to enlarged scale, of the brake-beam and corresponding brake-head connected thereto according to my improvement; Fig. 6, a horizontal section through the same on lines 6 6 in Fig. 5, and Fig. 7 a rear view of the brake-head detached from the beam.

Like letters and numerals of reference denote like parts in all the figures.

a represents my improved brake-beam, which is of the trussed order, comprising a compression member which consists, preferably, of a rolled I-shaped iron bar *b*, having its web 1 vertically arranged, and a tension member or rolled circular-shaped iron bar *c*, which is fixed at its end portions, together with the brake-heads *d*, to the corresponding portions of the compression-bar *b* and held apart from the bar *b* in the middle of the beam *a* to form a truss therefor by the brake-lever fulcrum *e*, as hereinafter more particularly described. The compression-

bar *b*, tension-bar *c*, and brake-heads *d* are 55 interlocked and firmly secured together near each end of the brake-beam, preferably by an eyebolt *f*, having its eye or opening on the inside of the compression member *b* and its shank 2 projecting through the web 1 of 60 the said member, against which it is clenched by a nut 3. Each brake-head *d* is formed on its rear side with a projecting bracket 4, which is suitably shaped and adapted to fit closely between the top and bottom inside 65 flanges 5 5' and against the web 1, respectively, of the compression-bar *b*. The bracket 4 is preferably hollow or box-shaped in cross-section and formed with an opening through its outer wall 6 opposite to the rear 70 side of the brake-head *d* for receiving the eye-ring of the bolt *f*, which fits closely therein between the side walls 6' of the bracket 4, the side walls 6' having circular openings therethrough registering with the opening 75 of the eyebolt *f* and corresponding diametrically to the preferably straight end portion thereof of the tension-bar *c*, which passes through the said openings to a suitable distance beyond the end of the compression-bar *b* and the corresponding surface of the brake-head *d*, from which projects an upright lug 7, the projecting part of the tension-bar *c* being screw-threaded and provided with a nut 8, having a projection 8' on 80 its inner face, which is adapted to engage in a correspondingly shaped groove 9, formed in the outside face of a preferably rectangular-shaped washer-plate *g*, placed on the tension-bar *c* between the nut 8 and the end 90 of the compression-bar *b*, whereby when the parts are assembled and the washer-plate *g* forced by the nut 8 against the end of the compression-bar *b* with its inner upright edge engaged by the lug 7 on the brake-head *d* 95 the tension-bar *c* is tightened until the projection 8' on the nut 8 is finally forced into engagement with the groove 9 in the washer-plate *g*, when the compression-bar *b*, tension-bar *c*, and brake-head *d* will be interlocked 100 and firmly held together in place. Furthermore, for relieving the strain at its junction with the compression and tension bars *b* and *c* each brake-head *d* is preferably formed on its rear side at the top with an overhanging 105 arm or bracket 10, which is adapted to bear constantly against the top side of the compression-bar *b*, as seen particularly in Fig. 5.

The brake-lever fulcrum *e*, which is of the usual form, is in the present case made in two parts, the body or perforated bifurcated part 11 for the pivot-pin of the brake-lever 5 being preferably of wrought-iron fixed at its base to the web 1 of the compression-bar *b* by a bolt 12, and the end or bearing part 13 for the tension-bar *c*, of cast-iron, having recesses 13' for receiving the end portions 10 of the body 11, which are secured to the end part 13 by a rivet 14. On the tension-bar *c* adjacent to each brake-head *d* is fixed a wrought-iron clamp *h* by a bolt 15, to which is coupled the end of the hanger-chain. 15 (Not shown.)

By the above construction of brake-beam the brake-heads are rigidly held in their proper relative position to the compression member at all times and the several parts of the brake-beam thereat securely interlocked. 20

What I claim as my invention, and desire to secure by Letters Patent, is—

1. In a brake-beam for a railroad-car, the combination of a compression member, an 25 eyebolt fixed to the said member adjacent to each end thereof, a brake-head having a bracket adapted to bear against the said member, and having an opening transversely therethrough for registering with the opening 30 of the said bolt, a tension member having screw-threaded end portions adapted respectively to pass through the said openings, a nut on the said portion, a washer between the nut and the end of the compression member, a brake-lever fulcrum intermediate to 35 the said members at their middle portions,

and means for fixing the said fulcrum to the compression member, substantially as described.

2. In a brake-beam for a railroad-car, the 40 combination of an I-shaped compression member, an eyebolt fixed to the said member adjacent to each end thereof, a brake-head having a bracket adapted to fit between the flanges and web of the said member, and having an overhanging arm adapted 45 to bear against the top of the said member, the said bracket having an opening transversely therethrough for registering with the opening of the said bolt, a lug on the brake-head adjacent to the said bracket, a circular-shaped tension member having screw-threaded end portions adapted respectively to pass through the said openings, a nut on the said portion having a projection, a washer interposed between the nut and the end of the compression member and adapted to engage the said lug, the said washer having a groove 50 adapted to be engaged by the said projection, a brake-lever fulcrum intermediate to 55 the said members at their middle portions, and means for fixing the said fulcrum to the compression member, substantially as described.

In testimony whereof I have signed my 60 name to this specification in the presence of two subscribing witnesses.

JOSHUA B. BARNES.
